UNITED STATES PATENT OFFICE

167,154

FISH LURE

James R. Lacy, Hot Springs, Ark.

Application February 25, 1952, Serial No. 18,656

Term of patent 14 years

(Cl. D31—4)

To all whom it may concern:

Be it known that I, James R. Lacy, a citizen of the United States, residing at Hot Springs, in the county of Garland and State of Arkansas, have invented a new, original, and ornamental Design for a Fish Lure, of which the following is a specification, reference being had to the accompanying drawing, forming a part hereof.

Figure 1 is a side elevation of a fish lure, showing my new design;

Figure 2 is a top plan view;

Figure 3 is a bottom plan view; and

Fig. 4 is a front view thereof.

I claim:

The ornamental design for a fish lure, as shown.

JAMES R. LACY.
